UNITED STATES PATENT OFFICE.

WILLIAM F. VEBER, OF BOWLING GREEN, OHIO, ASSIGNOR TO CHARLES D. YONKER, OF SAME PLACE.

LAMP-FILLING CAN.

SPECIFICATION forming part of Letters Patent No. 289,585, dated December 4, 1883.

Application filed September 27, 1883. (No model.)

To all whom it may concern:

Be it known that I, W. F. VEBER, of Bow-
ling Green, in the county of Wood and State of
Ohio, have invented certain new and useful Im-
5 provements in Lamp-Filling Cans; and I do
hereby declare that the following is a full, clear,
and exact description thereof, reference being
had to the accompanying drawing, and to the
letters of reference marked thereon, which
10 form part of this specification, in which—

The figure represents a vertical central sec-
tion through a coal-oil can or box having a
screw-threaded cap, a tube applied thereto, and
a shut-off cock, also showing a fixed pipe ex-
15 tending to a point near the bottom of the ves-
sel and valves.

This invention relates to portable vessels
which are adapted to contain what is known
as "burning-fluid," "coal-oil," and other light
20 hydrocarbon oils which are inflammable when
oxygen or air is brought in contact with them
and a flame is applied.

The object of my invention is to avoid the
danger which always attends the filling of a
25 lamp wherein light hydrocarbon fluid is used;
and it consists in the novel device, which will
be fully described, when the following de-
scription is considered in connection with the
annexed drawing.

30 The can or vessel A is adapted to contain
the light hydrocarbon fluid which is now used
for illumination. This can is provided with
the screw-threaded cap, which should fit gas-
tight, and for this purpose it is provided with
35 an india-rubber gasket.

The vessel which I show in the annexed
drawing has a cone-shaped top, A', having a
shoulder, a, rising from which is a spur-neck,
b, and on this neck is formed a male screw-
40 thread adapted to receive a female screw-
threaded cap, B, having a tube, c, to which a
valve, B', is applied, which will close gas-

tight. On this tube c a flexible tube, C, is ap-
plied having a mouth-piece, C'.

G designates a rigid tube, which is perma- 45
nently fixed gas-tight to the top of the vessel
A, and is provided with a valve, v. The
lower end of this tube extends nearly to the
bottom of said vessel. The upper end of this
tube protrudes above the top of the vessel, 50
and has applied to it a flexible tube, T, hav-
ing a nozzle, t, on its free end.

The operation is as follows: The can being
full of fluid, the nozzle t of the tube T is intro-
duced into a lamp, and the fluid from said 55
vessel is forced from the can into the lamp by
blowing through the tube c. It will be ob-
served that I apply to the cap of the can a
blowing-tube having a valve, which will pre-
vent the evaporation of the fluid; also, that I 60
apply to the outlet-tube another valve, v, which
will also prevent the evaporation of fluid from
the vessel A. By blowing from the lungs
through the flexible tube c, which is applied
to the top of the vessel A, and opening both 65
of the valves, the fluid in said vessel can be
caused to flow into a lamp peg or body. Then
by closing the two valves the vaporization of
the oil in the can is prevented.

Having described my invention, I claim— 70

In a filling-can, the screw-threaded cap hav-
ing a rigid tube, c, provided with a valve, B',
and a flexible tube for the induction of air, in
combination with the tube G, having a regu-
lating-valve, v, the flexible tube T, and nozzle 75
t, applied to this latter, all constructed and
adapted to operate substantially as described.

In testimony that I claim the foregoing as
my own I affix my signature in presence of
two witnesses.

WILLIAM F. VEBER.
